A. M. Carlsen.

UNITED STATES PATENT OFFICE.

WILFRED J. JANDRON, OF ST. PAUL, MINNESOTA.

COIN-OPERATED VENDING-MACHINE.

1,299,835.

Specification of Letters Patent.

Patented Apr. 8, 1919.

Application filed March 11, 1918. Serial No. 221,618.

To all whom it may concern:

Be it known that I, WILFRED J. JANDRON, a citizen of the United States, residing at St. Paul, in the county of Ramsey and State 5 of Minnesota, have invented a new and useful Coin - Operated Vending - Machine, of which the following is a specification.

This invention relates to coin-operated vending machines, and the object is to provide a capacious, cheap, simple and easily 10 operated machine of said kind for disposing of chewing gums and other articles put up in small packages and placed for sale to the public without any salesman or clerk to attend to the sales.

In the accompanying drawing, Figure 1 is a top or plan view of the improved vending machine with the cover removed and some of the duplicate parts omitted. Fig. 20 2 is a section on the line 2—2 in Fig. 1, the machinery inside being intact except that the shaft 19 and lever 27 to the right are intersected as on the line a—a to the left in Fig. 2. In this view, the cover is shown in 25 section and the main frame or casing of the machine is reduced in height by breaking away the middle portion of it, and a portion of the wall 6* is also broken away to expose the goods-lifting shelf 14 and rod 12 back 30 of it. Fig. 3 is a left side view of a small portion of Fig. 2. Fig. 4 is an enlarged section on the line b—b in Fig. 2 with the coin-controlling wheel slightly modified.

Referring to the drawing by reference 35 numerals, 5 designates a hollow preferably four-cornered base, upon which is fixed a goods cabinet 6 having in each of its four walls an outlet port 7 for goods. In the middle of said cabinet is fixed a tower 8 having four lateral wings 9 which together 40 with the tower and the cabinet 6 produce four goods magazines 10, 10, 10, 10 one adjacent each of the ports 7.

Slidably guided in a vertical groove 11 in 45 each side of the tower 8 is a rod 12 having at its upper end a finger catch 13 and at its bottom end a skeletonized or fork-like shelf 14, upon which the goods are piled as indicated by the packages 15. 15^a shows a 50 partly ejected package and 15^b packages delivered from the magazines upon the base ready to be removed. All the magazines are protected by a single cover 16, which may be secured by any suitable means against 55 unwarranted access to the goods.

The coin controlled delivery devices, one at each port 7, being all alike only one of them need be described and is as follows: The port 7 is normally closed or obstructed by one of four radial arms 17 of a wheel or 60 spider 18. Said spider is fixed on a horizontal shaft 19 which is journaled in a stand 20 and in one wall of the base; it projects beyond said wall and is there provided with a finger operated wheel or spider 21, which 65 is partly concealed and protected by a housing 22. Fixed on the shaft 19 is also a wheel 23 having four cams 24, each with a shoulder 25 at the base of it, (see Fig. 4 and to the right and left in Fig. 2).

Adjacent each wheel 23 is fulcrumed at 25 in a post 26 a lever 27, having at one end a lateral arm 28 which normally partly obstructs the lower end of a coin chute 29. The other end of the lever is normally held 75 down by a weight 30 fixed on it, so it rests with a lateral pin 31 in the lower end of a slot 32 in a vertical arm 33 of a weight 34, which normally rests upon a support 35.

The machine as illustrated is supposed to 80 be operated by five cent pieces, one of which is shown as 36 in Fig. 2. No larger coin will pass down the chute, and if a coin of a smaller size be dropped in, it passes through without operating the lever 27. But if a 85 "nickel" or five cent piece, or any other size diameter of coin for which the machine is intended to be operated, be dropped into the chute, the coin will act on the lever 27 to the extent of tilting it beyond the adjacent shoulder 25 of the wheel 23; in that position the pin 31 engages the upper end of the slot 32 and thereby holds the lever in a partly tilted position but still supporting the coin. The operator is then to take hold 90 of the finger wheel 21 and pull the upper arm of it from the left to the right position as indicated by the arrow 37 in Fig. 3. This turning movement of the shaft causes the adjacent cam 24 to further depress the lever 27 until the coin drops into the base and one of the arms 17 ejects one of the packages out upon the base, said arm passing as from 17^a to 17^b in Fig. 2, and leaves arm 17^a in the position 17^b so as to guard the port 7. This 100 last mentioned operation of the lever 27 being caused by the cam face 24, it raises the weight 34 while the cam passes the lever, whereupon the lever 27 and the weight 34 drop again into normal position so that the 110

next shoulder 25 of the wheel will engage the lever and prevent operation of the machine until another coin of the right size has been deposited in the chute. In order 5 to reach more easily all sides of the machine, the latter is mounted to rotate on a stud A fixed in a plate B, which plate may be secured by screw C upon a counter or other support D.

10 What I claim is:—

1. In a coin operated vending machine, a hollow base, a plurality of goods magazines fixed upon the base and having each an outlet port for goods and arranged to operate 15 in each port a spider wheel adapted to eject goods by one of its arms at a time, a shaft fixed in said spider and journaled in the hollow base and having one end extended beyond the base, a wheel on the shaft and 20 having its periphery formed with cams corresponding in numbers to the number of arms on the spider, each of said cams having near its base a radial shoulder, a coin chute, a horizontal beam lever fulcrumed in the 25 base and having a light end partly obstructing the lower end of the chute and a heavier and supported end arranged to hold the light end normally in its upper position and engaged with one of the cam shoulders, an 30 auxiliary weight arranged to engage the heavy end of the lever, and thus permit only

partial tilting of the lever by a coin in the chute, and means fixed on the outer end of the shaft for taking hold of in turning the shaft so as to overcome the auxiliary weight 35 and cause each cam to complete the tilting of the lever, whereby the coin is allowed to pass it and the spider to eject the goods paid for.

2. In a coin operated vending machine, 40 the combination with a coin chute, a beam lever having a heavy supported end, and a lighter end held in partly obstructing position at the lower end of the chute, an auxiliary normally supported weight near the 45 heavy end of the lever and being connected to said lever by a joint having a vertical play in it, a shaft and hand operated means for rotating it, a spider fixed on the shaft and arranged to feed the goods from the 50 machine an equal amount by each arm, a cam wheel fixed on the shaft and having a cam for each arm on the spider, and near each cam a shoulder for the light end of the lever to engage and arrest rotation of the 55 shaft until a coin has acted on the lever to tilt it into position to be further operated by the cam against the resistance of the auxiliary weight.

In testimony whereof I affix my signature. 60

W. J. JANDRON.
